DRAWER LATCH

Carl F. Wolters, New Canaan, Conn., assignor to
Remington Rand Inc., New York, N. Y., a corporation of Delaware

Application October 6, 1950, Serial No. 188,794

10 Claims. (Cl. 312—320)

This invention relates to a drawer latch for filing cabinets and the like and particularly to such latches adapted for use with filing cabinets having drawers in which a latch member on the drawer cooperates with a stationary keeper, mounted on the cabinet and forming a part of the drawer supporting and guiding means, to hold the drawer in closed position.

The invention comprehends a latch mechanism of the type mentioned above in which a very small number of parts are employed and in which the supporting and guiding means for the latch bar provides means for spacing elements of the drawer structure.

The invention provides a latch mechanism which is simple in construction, occupies a minimum amount of space, is very durable, and is economical to produce.

The invention further provides a latch construction which is readily mounted in place, is easily operated, and is positive in its operation, and a construction of certain drawer elements which increases the rigidity thereof and reduces the space required by a file cabinet in which drawers incorporating the improvements are used. Other advantages of the latch construction of the present invention and the associated drawer and cabinet construction will be perceived from the following description.

In the drawing:

Fig. 1 is a fragmentary, horizontal cross-section through part of a cabinet and file drawer incorporating the latch mechanism of the present invention, taken on the line 1—1 of Fig. 2.

Fig. 2 is a fragmentary, vertical cross-section of portions of the file drawer and cabinet shown in Fig. 1 from inside the drawer looking toward the front thereof, with portions of the drawer structure removed and the latch mechanism shown in elevation.

Fig. 3 is a partially exploded view in perspective of the latch mechanism of the present invention and the drawer handle associated therewith, a portion of the front panel of the file drawer being shown in dot and dash lines.

In Figs. 1 and 2 numeral 10 designates a file cabinet adapted to receive one or more drawers 12. The cabinet 10 comprises a side panel 11 and a frame member 13. Each of the drawers 12 comprises a front wall or panel 14, an interior cover plate 16 and side walls 18 which are attached, preferably by welding, to a rearwardly extending flange 15, formed on each side of the front panel 14. The side walls 18 carry on their outer sides a drawer slide 20 which is adapted to cooperate with

suitable means (not shown) in the cabinet 10 for supporting and guiding the drawer on case slide 22 in movement into and out of the said cabinet.

A handle 22 is provided on the outside of the front panel 14 of drawer 12. The ends 24 of the handle 22 are enlarged to form bearing surfaces for contact with the panel 14 and carry screw threaded studs 26 which extend rearwardly from the main portion of the handle 22 and pass through and support a latch guide plate 28 and inner cover plate 16, the handle being held in place by nuts 27 on the ends of the threaded studs 26. The front panel 14 is provided at a point opposite handle 22 with a depressed portion 32 which is preferably elliptical in shape. The depression 32 provides clearance for the fingers of a person moving the drawer by means of handle 22 and is of such depth that the flattened bottom 33 thereof, which lies in a plane parallel with the main portion of panel 14, will contact and support the center portion of cover plate 16 when the drawer is assembled.

The latch mechanism of the present invention is carried in the interior of drawer 12 adjacent or on the back of the front panel 14 thereof and comprises four principal parts—a guide plate, a latch bar, a spring, and a latch actuator. The guide plate 28 is preferably formed from an elongated piece of sheet metal and comprises a body portion 30 and, located on opposite sides of the depressed portion 32 on the front panel 14, a pair of upwardly extending mounting portions or hangers 31. Each of the upwardly extending hangers 31 is preferably formed integrally with the body portion 30 and located adjacent the ends thereof. The hangers 31 are preferably offset forwardly of the body portion 20 by longitudinally extending joggles 35 and each is provided with an orifice through which there may pass one of the studs 26 of handle 22 for supporting latch plate 28. The sides and top of hangers 31 are bent rearwardly to form spacer flanges 32. The ends of body portion 30 are also bent rearwardly at right angles to the rest of body portion 30 to form flanges or projections 33 and 34 which are provided with aligned slots 36 and 38, respectively, adapted to receive and guide a horizontally, transversely movable latch bar 40.

The latch bar 40 is preferably formed from a single strip of flat sheet metal to provide an elongated central portion 42 which is slidably received within slot 36 of the guide plate 28. The latch bar 40 at one end of the elongated central portion 42 is provided with a narrow extension 44 which is aligned with the elongated central por-

tion 42 and is preferably formed integrally therewith. The extension 44 is slidably received within the slot 38 in the flange 34. At the other end of the elongated central portion 42, latch bar 40 is bent upwardly and rearwardly as indicated by the numeral 46. A horizontal, rearwardly directed, L-shaped latch 48 is preferably formed integrally with a straight portion 47 of the bar 40 which extends outwardly from the bent portion 46 in a horizontal plane substantially parallel to the central portion 42 of bar 40.

The latch 48 has a rounded rear face 50 and a forward face 52 which is flat and parallel to the central portion 42 and which is adapted to cooperate with a keeper 54 having a flat rear face 56 and a bevelled or inwardly inclined portion 58. The keeper 54 is preferably integrally formed on a metal strip 55 which is attached by suitable means such as a screw 60 to the inwardly projecting case slide 62. The case slide 62 is carried by the cabinet frame member 13 and is formed and mounted in any well-known or suitable manner to cooperate with the drawer slide and other mechanism (not shown) with which the drawer and cabinet are customarily equipped.

A latch actuator 66 is provided to permit movement of the latch bar 40 from the outside of the drawer. The latch actuator 66 is preferably formed in one piece and is provided with a vertically extending portion 68 having on its lower end a rearwardly offset vertical flange 70 which is adapted for mounting on the elongated central portion 42 of the latch bar 40 by means such as a screw 72. The actuator 66 is rigidly attached to the latch bar 40 since the bent portion 74 of the latch actuator 66 intermediate the vertical portion 68 and flange 70 is adapted to rest on the top of the latch bar 40 and thus prevents pivotal movement of the latch actuator 66 with respect to the latch bar. An outside trigger or finger 76, 40 horizontally movable and adapted for manual engagement, is connected to the top of the vertical portion 68 of the latch actuator 66 by a horizontal portion 78 which passes through a slot 80 in the wall of the depressed portion 82 45 of the front panel 14. The trigger 76 is preferably situated between the handle 22 and the front drawer panel 14 where it will be protected from accidental movement.

A coil spring 84 is provided to bias latch bar 40 and latch 48 in position to engage with the keeper 54. The spring 84 surrounds the narrow portion 44 at one end of latch bar 40 with the ends of the spring engaging, respectively, flange 34 of guide plate 28 and the end of the elongated central portion 42 of latch bar 40. Movement of latch bar 40 by spring 84 is limited by the engagement of latch actuator 66 with the wall of the depressed portion 82 of front drawer panel 14.

The cover plate 16 is employed in the interior of the drawer 12 to cover the latch mechanism. The cover plate 16 is formed from a piece of sheet metal of suitable size and comprises a generally flat portion 86 and forwardly turned flanges 88 on the four sides thereof. The flat portion 86 of the cover plate 16 is provided with two spaced-apart cup-like depressions 90 in which there are perforations to receive the threaded studs 26 of handle 22. A notch 92 is formed in one of the flanges 88, the notch being so disposed and of such size as to pass over the horizontal portion 47 of latch bar 40.

In assembling a file drawer with the improved latch mechanism of the present invention latch bar 40 is inserted through a slot 94 in flange 15 75

of outer drawer head 12 with the L-shaped latch 48 directed toward the rear of the drawer so that the flat portion 52 thereof faces forwardly. The forward edge of side wall 18 is notched out, in registry with slot 94, to accommodate insertion of latch bar 40. The bar 40 is then inserted through slot 36 of guide plate 28. Next, spring 84 is placed around the narrow portion 44 of latch bar 40 and the end of portion 44 is passed through slot 38. The trigger 76 of latch actuator 66 is then passed outwardly through the slot 80 in the front drawer panel 14 and flange 70 of the latch actuator is attached to the elongated central portion 42 of bar 40 adjacent its juncture with the narrow portion 44. Following this, handle 22 is placed in position on the front of panel 14 with threaded studs 26 passing through the panel and hangers 34 of guide plate 28. The cover plate 16 is then placed in position with the cup-like depressions 90 opposite threaded studs 26 and with notch 92 in position to pass around latch bar 40. The studs 26 are then passed through the perforations in depressions 90 and nuts 27 are applied to the studs thereby holding cover plate 16 and guide plate 28 in position on the back of front panel 14. When thus assembled, cover plate 16 is spaced from front panel 14 by the rearwardly directed flanges 32 of hangers 34 of guide plate 28 and the flattened central portion 83 of the depressed portion 82 in panel 14 contacts and supports the center of plate 16.

The operation of the drawer latch of the present invention is simple, there being in effect only two moving parts, the latch bar 40 and the spring 84. Movement of the trigger 76 of the latch actuator 66 to the right (as depicted in the drawing) moves latch bar 40 to which the latch actuator is attached, thus disengaging the integrally formed latch 48 from keeper 54. In so disengaging latch 48, spring 84 is compressed and upon release of trigger 76 latch bar 40 will be returned to its normal position by the spring. When the drawer is moved from open to closed position, the rounded portion 50 of latch 48 contacts the beveled portion 58 of keeper 54 and is laterally displaced while compressing spring 84. As soon as flat portion 52 of the latch has passed the end of the inclined portion 58 of the keeper, the spring returns the latch to normal position in which the flat faces 52 of the latch and 56 of the keeper are in contact so that drawer 12 will be securely held in closed position.

The drawer latch of the present invention is highly advantageous for a number of reasons. In the first place, the compactness of the latch mechanism and the fact that all movement of parts is in a direction transverse of the drawer permits the cover plate 16 to be placed closer to the front panel 14 of the drawer 12 than would otherwise be the case. With drawers of the same outside dimensions, the amount of filing space in a drawer equipped with the present latch will, therefore, be greater than that provided in a drawer in which a latch mechanism is used which requires space for operative movement longitudinally of the drawer.

In the second place, the cost of manufacturing drawers equipped with the drawer latch of the present invention will be reduced since the latch employs only a small number of simply formed parts and since the latch guide plate 28 not only provides support for the latch bar 40, the latch 48, and mounting means for the spring 84, but it also provides, through the medium of the flanges 32, means for accurately spacing

the cover plate 16 from the front panel 14 and thus simplifies the assembly of the drawers.

The reduction in the overall length of filing cabinets constructed as described herein is important because of the increasing difficulty of providing the necessary space for files in business offices. Accordingly, the counter-sinking or depression of the front panel 14 of the drawer 12 behind the handle 22 is a noteworthy advantage since the handle may consequently extend for a shorter distance beyond the front of the drawer and the overall length of the cabinet may be decreased. This feature together with the increased amount of filing space in a drawer equipped with the latch of the present invention makes the construction herein described most valuable.

It may also be noted that forming the depressions 82 and 90 in the front panel 14 and the cover plate 16, respectively, results in increasing the stiffness of the metal sheets and consequently in stronger construction.

The invention claimed is:

1. In a filing cabinet having a drawer with a front wall and side walls, means in said cabinet along the sides of said drawer supporting and guiding said drawer for movement into and out of said cabinet, a handle on the front wall of said drawer, a hand-receiving recess in said front wall disposed symmetrically to said handle and a cover plate within said drawer and spaced from the front wall thereof, the combination therewith of a latch guide plate mounted on said front wall of said drawer including spaced slotted projections rearwardly extending therefrom, a latch bar slidably mounted in said slotted projections in said guide plate for horizontal transverse movement, a latch actuator carried by said latch bar and having a horizontal extension parallel to the front wall projecting through a side portion of said recess in said front wall and adapted to be manually engaged, resilient means interposed between said actuator and one of said projections to normally urge said latch bar in one direction, a latch carried by said latch bar and adapted for engagement with a keeper carried by a portion of said drawer supporting and guiding means, threaded studs passing through said front panel, said latch guide plate and said cover plate, nuts on said studs, said handle, guide plate, and cover plate being supported by said threaded studs and held in place by said nuts.

2. In a filing cabinet having a drawer with a front wall and side walls, means in said cabinet along the sides of said drawer supporting and guiding said drawer for movement into and out of said cabinet, a handle on the front wall of said drawer, a hand-receiving recess in said front wall disposed symmetrically to said handle, and a cover plate within said drawer and spaced from the front wall thereof, the combination therewith of a latch guide plate mounted on said front wall of said drawer, integrally formed slotted projections rearwardly extending from said guide plate, a latch bar slidably mounted in said slotted projections in said guide plate for horizontal transverse movement, a latch actuator carried by said latch bar and having a horizontal extension parallel to the front wall projecting through a side portion of said recess in said front wall and adapted to be manually engaged, resilient means interposed between said actuator and one of said projections for urging said latch bar in one direction

and compressible by movement of said latch bar in the opposite direction, a latch carried by said latch bar and adapted for engagement with a keeper carried by a portion of said drawer supporting and guiding means, threaded studs mounted on said handle and passing through said front wall, said guide plate and said cover plate, nuts on said studs, said guide plate and said cover plate being supported by said threaded studs and held in place by said nuts, and said guide plate having thereon rearwardly projecting flanges disposed adjacent to and cooperable with said threaded studs to position said cover plate in fixed spaced relation from said front wall.

3. In a filing cabinet having a drawer with a front wall and side walls, means in said cabinet along the sides of said drawer supporting and guiding said drawer for movement into and out of said cabinet, a handle on the front wall of said drawer, a hand-receiving recess in said front wall disposed symmetrically to said handle and a cover plate within said drawer and spaced from the front wall thereof, the combination therewith of a latch guide plate mounted on said front wall of said drawer, integrally formed plural flanges and slotted projections rearwardly extending from said guide plate, a latch bar slidably mounted in the slotted projections and spaced from said flanges in said guide plate for horizontal transverse movement, a latch actuator carried by said latch bar and having a horizontal extension parallel to the front wall projecting through a side portion of said recess in said front wall and adapted to be manually engaged, a spring circumjacently disposed on said latch bar between said actuator and one of said slotted projections and adapted to yieldably resist movement of said latch bar in one direction, a latch on one end of said latch bar adapted for engagement with a keeper carried in a fixed position by said cabinet relative to said latch and said drawer supporting and guiding means, threaded studs attached to said handle and passing through said front wall, said guide plate and said cover plate, nuts on said studs, said guide plate and said cover plate being supported by said threaded studs and held in place by said nuts, and said flanges or said guide plate arranged to cooperate with said studs to position said cover plate in fixed spaced relation from said front wall.

4. In a file cabinet having a drawer with a front wall and side walls, means in said cabinet along the sides of said drawer supporting and guiding said drawer for movement into and out of said cabinet, a handle on the front wall of said drawer, a hand-receiving recess in said front wall disposed symmetrically to said handle and a cover plate within said drawer and spaced from the front wall thereof, the combination therewith of a latch guide plate mounted on said front wall of said drawer, integrally formed rearwardly extending flanges on said guide plate, a pair of spaced rearwardly extending projections integrally formed from said guide plate and spaced from said flanges, aligned vertically disposed slots in said projections, a latch bar slidably mounted in said slots for horizontal transverse movement, a latch actuator carried by said latch bar and having a horizontal extension parallel to the front wall projecting through a side portion of said recess in said front wall and adapted to be horizontally moved by manual engagement, a spring circumjacently mounted

on said latch bar and interposed between said actuator and one of the slotted projections for resiliently resisting movement of said latch bar in one direction, a latch on one end of said latch bar adapted for engagement with a keeper carried by a portion of said drawer supporting and guiding means, threaded studs extending rearwardly from said handle and passing through said front wall, said guide plate and said cover plate, nuts on said studs, said guide plate and said cover plate being supported by said threaded studs and held in place by said nuts, and said flanges on said guide plate being disposed adjacent to said studs to space said cover plate from said front wall and concurrently position said guide plate supported latch in aligned relation with said keeper.

5. A drawer latch mechanism adapted to be mounted in a drawer having a front wall and an inner cover plate, a handle affixed to said front wall having threaded portions extending through said wall and said cover plate, a depressed recess in said front wall rearwardly extending from said handle, said latch mechanism comprising a guide plate having a body portion and a pair of upwardly extending hangers having apertures therein adapted to receive said threaded handle portions to position said guide plate between said front wall and said cover plate, the ends of said body portion being turned rearwardly to provide integral projections, slots in said projections, a latch bar carried by said guide plate and having slidable engagement in said slots, a spring circumjacently mounted on said latch bar and having engagement with said guide plate for urging said latch bar in one direction, a latch carried by said latch bar and adapted to engage with a keeper, and a latch actuator attached to said latch bar and having a portion extending to the outside of said drawer through an aperture in said front wall recess, said latch actuator being manually operable to move said latch bar against the action of said spring, said hangers having rearwardly directed spacing flanges integrally formed therewith for spacing said cover plate substantially the depth of said recess from said front wall, whereby said cover plate abuts against said recessed front wall portion and is reinforced thereby.

6. A drawer latch mechanism adapted to be mounted in a drawer having a front wall, a forwardly extending handle thereon, and a cover plate, a depressed recess in said front wall, rearwardly extending under said handle, said latch mechanism comprising a substantially U-shaped guide plate having a body portion and a pair of upwardly extending hangers adapted to receive said recessed portion therebetween, the ends of said body portion being turned rearwardly to provide projections, aligned slots in said projections, a latch bar carried by said guide plate and having slidable engagement in said slots, a spring circumjacently mounted on one end of said latch bar and having engagement with said guide plate for urging said latch bar in one direction, a latch carried by said latch bar on the other end thereof and adapted to engage with a keeper, and a latch actuator extending through said front wall recess and manually operable to move said latch bar against action of said spring, said hangers having rearwardly directed spacing flanges integrally formed therewith to position said cover plate away from said front wall substantially the depth of said recess, whereby said cover plate abuts against said front

10 wall recessed portion and is secured in spaced parallel relation with the remainder of said front wall.

7. A drawer latch mechanism adapted to be mounted in a drawer having a front wall, a forwardly extending handle thereon, and an inner cover plate, a rearwardly extending recess integrally formed in said front wall, said latch mechanism comprising a guide plate having an elongated body portion and a pair of upwardly extending hangers adapted to receive said recess therebetween, said hangers having means for supporting said guide plate, the ends of said body portion being turned rearwardly to provide projections, aligned slots in said projections, a latch bar carried by said guide plate and slidably mounted in said slots for horizontal transverse movement, a spring circumjacently mounted on one end of said latch bar and having engagement with one of said flanges for urging said latch bar in one direction, a latch carried by said latch bar and adapted to engage with a keeper, and a latch actuator attached to said latch bar and having a portion extending through an aperture in said front wall recessed portion to the outside of said drawer, said latch actuator being manually operable to move said latch bar against the action of said spring out of engagement with said keeper, said hangers having rearwardly directed spacing flanges integrally formed therewith to space said cover plate away from said front wall substantially the depth of said recess, whereby the cover plate abuts against the recessed portion of the front wall, the remainder of the front wall being secured in spaced relation from said cover plate.

8. In a file drawer having a sheet metal front wall and a handle thereon, the combination of a latch guide plate within said drawer adjacent the front wall thereof, a latch bar carried by said guide plate, a latch on one end of said latch bar adapted for engagement with a keeper, a latch actuator carried by said latch bar and having a portion extending through said front wall and adapted to be manually engaged, yieldable means resisting movement of said latch bar in one direction, a cover plate within said drawer, threaded studs carried by said handle and passing through said front wall, and nuts on said studs, said guide plate and said cover plate being supported on said studs and held in place by said nuts, said guide plate having thereon rearwardly projecting flanges spacing said cover plate from said front wall, and said front wall having a depressed portion contacting and supporting said cover plate.

9. In a file drawer having a sheet metal front wall and a handle thereon, the combination of a latch guide plate within said drawer adjacent the front wall thereof, a latch bar mounted in said guide plate for horizontal transverse movement, a latch on one end of said latch bar adapted for engagement with a keeper, a latch actuator carried by said latch bar and having a portion extending through said front wall and adapted to be manually engaged, yieldable means resisting movement of said latch bar in one direction, a cover plate within said drawer adjacent said front wall thereof but rearwardly of said guide plate and said latch bar, threaded studs carried by said handle and passing through said front wall, guide plate, and cover plate, and nuts on said studs, said guide plate and said cover plate being supported on said studs and held in place by said nuts, said guide plate having thereon

rearwardly projecting flanges spacing said cover plate from said front wall, and said front wall having a depressed portion therein adjacent said handle contacting and supporting said cover plate, said depressed portion reinforcing said sheet metal front wall and further providing finger space under said handle.

10. A drawer front and latch for filing cabinets, wherein the cabinet has means mounting a drawer for movement on guide means between open and closed positions, and a keeper is mounted on cabinet carried parts adjacent the front of said cabinet, comprising a front wall on said drawer formed intermediate its edges with a rearwardly offset section having a central portion lying in a plane spaced rearwardly of the plane of said wall, a cover plate mounted in spaced substantially parallel relation in the rear of said front wall with a central portion engaging the central portion of said offset section, a guide plate positioned between said front wall and cover having spacer flanges at opposite sides of and cooperating with said offset section in spacing said cover from said front wall, said guide plate having spaced guide flanges on opposite ends extending transversely to said front wall and formed with aligned guide slots, a latch bar extending through said guide slots and slidably supported in said guide projections for movement in a plane substantially parallel to said front wall; said latch bar having one end formed to provide a latch for engagement with said keeper to retain said drawer in closed position, a spring engaging one of said guide projections at one end having the opposite end secured to

said latch bar for normally moving said bar into latching position; a latch actuator having a strip attached to said latch bar, having an intermediate section in spaced parallel relation to said latch bar at the rear of said front wall, extending through a slot in said offset section and having a finger on the free end extending forwardly from the end of said intermediate section for manual engagement in the depression in said front wall formed by said offset section for manual operation of said latch bar, and a drawer handle mounted on said front wall having a handle section extending across said depression in said front wall, embracing said finger and having studs on the ends of said handle section extending transversely through said front wall, guide plate and cover at opposite sides of said offset section with cooperating means on the ends of said studs securing said front wall, guide bracket and cover plate in assembled relation.

said latch bar for normally moving said bar into latching position; a latch actuator having a strip attached to said latch bar, having an intermediate section in spaced parallel relation to said latch bar at the rear of said front wall, extending through a slot in said offset section and having a finger on the free end extending forwardly from the end of said intermediate section for manual engagement in the depression in said front wall formed by said offset section for manual operation of said latch bar, and a drawer handle mounted on said front wall having a handle section extending across said depression in said front wall, embracing said finger and having studs on the ends of said handle section extending transversely through said front wall, guide plate and cover at opposite sides of said offset section with cooperating means on the ends of said studs securing said front wall, guide bracket and cover plate in assembled relation.
